DOFFING MECHANISM FOR RING SPINNING,
DOUBLING, AND TWISTING MACHINESJames Jackson Haythornthwaite, Accrington,
England, assignor to T. M. M. (Research) Limited,
Rossendale, EnglandApplication November 16, 1950, Serial No. 195,961
In Great Britain November 29, 1949

7 Claims. (Cl. 57—54)

1

The invention has for its object to provide in a ring spinning, doubling or twisting machine, improved means for removing or doffing the yarn packages from the spindles at the completion of the spinning operation, i. e. when the build of a full yarn package is complete, such means being applicable whether the relative reciprocatory motion between the spindles and the rings necessary for the formation of the yarn packages is effected by raising and lowering the spindle rail in relation to a stationary ring rail, or by reciprocating movement of the ring rail in relation to a stationary spindle rail, or by a combined movement of both these elements in opposite directions.

In a ring spinning, doubling or twisting unit according to the invention, I provide mechanism for doffing the yarn package, comprising a carrier member detachably mounted on the spindle to form a support for the yarn package wound thereon, said carrier member being capable of axial and rotary movement relatively to the spindle, means for arresting rotation of the carrier member when the package reaches the doffing position, a catch on the carrier member for engaging the yarn so that, the carrier member being arrested and the spindles briefly rotated, the yarn is drawn taut at the base of the package, means for severing the yarn when so tautened, and interceptor means for retaining the carrier member at the subsequent separation of the spindle and the ring so that the yarn package is supported with freedom for doffing by lateral displacement.

The yarn-engaging catch and the yarn-severing means may both be mounted on the carrier member in such relationship that when the yarn is caught by the former it is drawn taut across a cutting edge of the latter.

The carrier member preferably provides a shrouded seating for the base of the bobbin, pirn or like tube on which the yarn package is wound on the spindle, said seating being of such character that when the spindle is withdrawn from the package the latter will be predisposed to topple laterally as the lateral support hitherto afforded by the spindle is removed.

The said interceptor may take the form of a narrow plate or bar supported slidably beneath the ring rail and extending throughout the length of the machine or of a unitary section thereof, with a connection at one end to means by which the plate or bar may be reciprocated so that projecting portions thereof are engaged with or disengaged from a flange on each package carrier member. Preferably, two such plates are provided, being disposed in spaced parallel arrange-

2

ment one in front of and the other behind the spindle axes, with a yoke connecting said plates at one end to the means employed for their reciprocatory movement.

The manner in which the invention may be carried into effect is hereinafter described with reference to the accompanying diagrammatic drawings which illustrate an embodiment of the invention as applied to a ring spinning machine. 5 In said drawings, Fig. 1 is a general arrangement of a spinning unit, as viewed on a section at right angles to the spindle and ring rails, the parts being shown in the spinning position; Figs. 2 and 3 are partly sectional perspective views of the 10 package support member shown separately, as viewed respectively from opposite sides; Fig. 4 is a section of part of the spinning unit shown in Fig. 1 immediately after the spindle rail first reaches the doffing position, and Fig. 5 is a fragmentary section on the line V—V of Fig. 4; Fig. 6 is a similar view to Fig. 4, but depicts the second stage in the doffing cycle; Fig. 7 is a section on the line VII—VII of Fig. 6; Fig. 8 is a similar view to Fig. 1, showing the third stage in the 15 doffing cycle. (Figs. 2 to 8 are drawn on a somewhat larger scale than Fig. 1.) Fig. 9 is a section through a spinning machine, incorporating doffing mechanism as illustrated in Figs. 1 to 3, and in which the separator plates are adapted to be 20 moved outwardly to ensure positive doffing.

The spinning unit to which the present description relates comprises the known elements of a spindle 1, rotatably mounted in a bolster 2 which is suitably fixed in the spindle rail 3, the spindle 25 wharve being indicated at 4. During the spinning operation, the yarn package is built upon a bobbin, pirn or like tube which is placed upon the spindle, the nose of the package being arranged to project through a ring 6 carried in a ring rail 7. The traveller is indicated at 8 and the lappet-guide at 9. Fig. 1 depicts the path of the yarn as it is drawn from the drafting apparatus (not shown) through the guide 9 and traveller 8 to the package 5. It will be understood that the 30 invention is applicable to ring spinning machines in which the relative reciprocating motion between the spindle and ring, necessary to perform the operation of building the yarn package, is 35 effected either by raising and lowering the spindle rail in relation to a stationary ring rail, or by raising and lowering the ring rail in relation to a stationary spindle rail, or by combined movements of both spindle rail and ring rail; it is however assumed for the purpose of the present 40 45 50 55

description that the spindle rail is the reciprocating element and that the ring rail is stationary.

Detachably mounted on the blade of the spindle 1 so that it rests upon the upper flange of the wharve 4 thereof, is a member 10 (herein referred to as the "package carrier") which has an axially bored cylindrical body, an upward annular extension 11 of somewhat larger diameter, and a thin basal flange 12 in the underside of which is fixed a peg 13 for a purpose to be described. A leather or other resilient washer 14 is interposed between said flange 12 and the wharve 4. The extension 11 has a broad upper face in which is mounted a catch comprising a spring leaf 15 and a pivotal block 16 which is urged to bear against the underside of the leaf 15 by a compressed spring 17. On the inner wall of the extension 11, at a point adjacent said catch 15, 16, is mounted a cutter consisting of a flat blade 18 having a vertical cutting edge 19.

The package carrier provides a shrouded seating for the bobbin, pirn or like tube upon which the yarn package is to be wound, the upwardly directed face of the body 10 of said package carrier being furnished with a quadrantal axial projection 20 which serves as a seat for the base of a bobbin or the like placed on the spindle, and said bobbin or the like being so located that the lowermost coil of yarn in the package wound thereon will occupy a position immediately above the upper face of the extension 11. The package carrier is made a loose fit upon the part 21 of the spindle blade 1 (see Fig. 8), so as to be capable of free axial and rotary movement in relation thereto.

The ring rail 7 is counter-bored beneath the ring 6 to provide a recess 22 capable of accommodating the flange 12 of the package carrier when the spindle is raised to the doffing position, i. e. the position of the spindle relative to the ring in which the whole of the yarn package projects upwardly through the ring.

On the underside of the ring rail 7 are slidably mounted two parallel interceptor plates 23 and 24; longitudinal slots 25 in the plates cooperate with studs 26 which depend from the rail 7 to guide the movement of the plates, the weight of the latter being supported by the heads of the studs. The two plates 23, 24 are arranged to serve a plurality of spinning units, and are adapted to be slidden endwise at the appropriate times by mechanical means linked to a yoke 27 which is attached to the ends of the plates, and operating in synchronism with the package-building and package-doffing mechanism. The plates 23 and 24 are fashioned with oppositely disposed inward lateral extensions 28 in respect of each spinning unit, and each extension 28 of the plate 23 includes a lug 29 so located that it will serve as an abutment for the peg 13 in the package support flange 12.

The doffing operation is performed in the following manner:

It is well known in ring spinning practice, that the yarn passing through the traveller between the drafting rollers and the spindle, causes the traveller to be revolved around the ring as the spindle rotates. The traveller rotates at a lesser speed than the spindle, thereby causing the yarn to be wrapped on the bobbin or pirn, the variation in speed of the traveller being governed by the delivery rate of the drafting rollers. Upon completion of the bobbin, the spindle rail 3 is raised to the doffing position (Fig. 4), whereupon rotation of the spindles and the drafting rollers

ceases. It will be noted that the yarn is now lying close against the upper face 11 of the package carrier, but it has not entered the catch 15, 16 as this cannot happen whilst the package carrier is rotating at spindle speed, and the traveller revolving at a slower speed in the same direction. The interceptor plates 23, 24 are then moved from the inoperative position shown in Fig. 5 to the position shown in Fig. 7, in which the lateral extensions 28 of the said plates lie beneath the flange 12 of the package carrier.

A brief rotational impulse is now imparted to the spindle, but the rotation of the package carrier in relation to the spindle is arrested by the impingement of the peg 13 against the lug 29 of the plate 23. Immediately the package carrier stops, the revolving yarn enters the catch 15, 16 thereby arresting the traveller, and as the spindle and bobbin continue part of a revolution the 20 yarn between the bobbin and the catch 15, 16 is severed against the cutter 18.

The relative positions of the catch 15, 16 and the peg 13 with respect to the spindle axis are such as to ensure that when the peg 13 abuts 25 against the lug 29 of the plate 23, the package carrier is stopped when the catch 15, 16 is in the rearmost position as shown in Figs. 6 and 8. This arrangement ensures that the catch arrests the traveller in its rearmost position, and that 30 the package is not impeded when this is doffed as hereinafter described.

The spindle rail 3 is now lowered, but the package carrier (and the bobbin or the like and the package supported thereon) are retained in the doffing position by the presence of the interceptor plates 23, 24 beneath the package carrier flange 12, so that when the spindle rail reaches its lowermost position the tip of the spindle blade has been withdrawn completely from the bobbin or the like. The seat 20 of the package carrier upon which the base of the bobbin or the like has been resting, is so located that when the peg 13 is arrested by the lug 29 said seat will occupy a rear position. This arrangement, and the restriction of the support afforded by the seat 20 to a quadrant of the base of the bobbin, combine to predispose the bobbin and package to topple forwardly as soon as the lateral support hitherto provided by the spindle has been removed, and doffing automatically occurs at this 50 stage.

If desired, the lateral displacement of the packages may be effected positively by an outward sweeping movement of the separator plates conventionally provided between adjacent spinning units, as shown in Fig. 9, for which purpose adjacent pairs of said plates 30 may be joined in the rear of each spindle position by a U-shaped connection which, when the plates are moved outwardly by the operation of a cam 31, as depicted at the right-hand side of Fig. 9, will push the package laterally from the package carrier, to fall in front of the machine. An arrangement wherein the casing of the machine is pivoted mechanically into a position in which it forms a hopper receiving the doffed yarn package and guiding it on to a conveyor for removal to a receptacle at the end of the machine, forms the subject of my co-pending United States Application No. 193,825, now Patent No. 2,570,057.

It will be understood that the translational movements of the spindle and the yarn package herein referred to are movements in relation to the ring rail and that the references herein contained to the package "reaching the doffing po-

sition" or the spindle being "withdrawn from the package" are intended to include the case in which the doffing position of the package is reached by a movement of the ring rail and in which the ring rail raises the package from the spindle.

What I claim as my invention and desire to secure by Letters Patent is:

1. A ring spinning, doubling or twisting unit comprising, in combination, a spindle, a spindle rail supporting the spindle, a ring, a traveller supported on the ring, a ring rail supporting the ring, said ring rail being located above the spindle rail and the rails being mounted for relative vertical movement, a yarn package carrier detachably supported on the spindle, normally frictionally driven by the spindle, and normally occupying a fixed vertical relation to the spindle, said carrier including a yarn catch and a severing member, an interceptor carried on the ring rail and shiftable into carrier supporting position to fix the vertical relation of the carrier to the ring rail preparatory to doffing, the interceptor including a stop member, said carrier including a stop member engageable with the interceptor stop member for arresting rotation of the carrier with the spindle and the yarn package in motion to cause the yarn to be caught and held taut by the carrier catch and to be severed by the severing member, the interceptor serving to retain the carrier at the subsequent separation of the rail so that the yarn package will be supported with freedom for doffing by lateral displacement.

2. A spinning or like unit as claimed in claim 1 in which the unit is organized to require doffing in a definite direction and in which the carrier includes a package engaging support for engaging the lower end of the package at only one side thereof, the support and the catch being located at the same side of the carrier, and the carrier and interceptor stop members being disposed to arrest the carrier with the support and the catch remote from the side of the unit toward which doffing is required to be effected.

3. A spinning or like unit as claimed in claim 1 in which the unit is organized to require doffing

in a definite direction and in which the carrier includes a package engaging support for engaging the lower end of the package at only one side thereof, the support and the catch being located at the same side of the carrier, and the carrier and interceptor stop members being disposed to arrest the carrier with the support and the catch remote from the side of the unit toward which doffing is required to be effected, the ring rail being formed with a recess in its under side for receiving the lower portion of the carrier when doffing is to be effected, and the interceptor including inwardly projecting members movable beneath the carrier and an operating member for shifting the interceptor.

4. A spinning or like unit as set forth in claim 1 in which the yarn catch and the severing member of the yarn package carrier are located side by side to cause the yarn when engaged by the catch to be drawn taut across a cutting edge of the severing member.

5. A spindle or like unit as set forth in claim 1 in which the package carrier comprises an axially bored body having an upward annular extension of larger diameter than the bore and a thin basal flange, the carrier stop consisting of a peg depending from the flange, and the extension having an upper face mounting the yarn-engaging catch and an inner wall mounting the severing member.

6. A spinning or like unit as set forth in claim 1 in which the interceptor comprises two plates at opposite sides of the spindle axis each including an inward projection insertable beneath the carrier, and an operating member rigidly connecting the plates to one another at their ends.

7. A spinning or like unit as set forth in claim 1 in which a member is mounted behind the vertical axis of each spindle for engaging the rear of the yarn package, and mechanism is provided for moving the member outward at the appropriate time to impel the yarn package outwardly to insure positive doffing.

JAMES JACKSON HAYTHORNTHWAITE.
